UNITED STATES PATENT OFFICE.

ELLSWORTH A. HAWTHORNE, OF BRIDGEPORT, CONNECTICUT.

ELECTRICAL CONNECTION.

1,353,748.

Specification of Letters Patent. Patented Sept. 21, 1920.

Application filed February 14, 1918. Serial No. 217,043.

To all whom it may concern:

Be it known that I, ELLSWORTH A. HAWTHORNE, a citizen of the United States, and a resident of Bridgeport, in the county of 5 Fairfield and State of Connecticut, have invented an Improvement in Electrical Connections, of which the following description, in connection with the accompanying drawings, is a specification, like characters on 10 the drawings representing like parts.

This invention relates to electrical connections, and is more especially, though not exclusively, concerned with a socket connection for electric lamps, although the invention is by no means restricted to use in 15 lamps, but is susceptible of general application.

My invention will be best understood by reference to the following description, when 20 taken in connection with the accompanying drawings of two specific embodiments thereof, while its scope will be more particularly pointed out in the appended claims.

In the drawings:—

25 Figure 1 is a central, longitudinal sectional view of a lamp equipped with an electrical connection embodying my invention;

30 Fig. 2 is a central, vertical, longitudinal sectional view, on an enlarged scale, of the electrical connection and the focusing device of the lamp;

Fig. 3 is a sectional view on line 3—3 of Fig. 2;

35 Fig. 4 is a sectional view on line 4—4 of Fig. 3;

Fig. 5 is a sectional view, similar to Fig. 4, but showing a slight modification, for 40 use in connection with what is known as a single wire lighting system;

Fig. 6 is a side elevation of another form 45 of electrical connection embodying my invention, showing the same equipped with an electric bulb;

Fig. 7 is a sectional view on line 7—7 of Fig. 6;

Fig. 8 is an elevation, viewed from the right-hand side of Fig. 6; and

Fig. 9 is an elevation, similar to Fig. 8, 50 but showing a slight modification, to adapt the same to a two-wire lighting system.

Referring to the drawings, and to the embodiments of my invention which I have shown for the purposes of exemplification, 55 and referring first more particularly to Figs. 1 to 4, inclusive, I have there shown

a common form of electric lamp, comprising a lamp casing 10, having a reflector 11, separated from said casing by a space 12, forming a chamber adapted to receive any one of the 60 electrical connections hereinafter described, either of which connections may be equipped with an incandescent electric bulb 13, associated with said reflector. In the present example, as a means for focusing the bulb with 65 relation to the reflector, I have shown focusing means, which forms the subject matter of a pending application. Such focusing means herein comprises a focusing rod 14, which is appropriately connected to the bulb 70 as hereinafter described, and extends in a rearward direction through the casing 10. As a means for securing the rod in the desired position, I have provided a nut 15, secured to the casing 10, and threaded to receive a clamping screw 16, the latter being provided with one or more longitudinal slots 75 17 to render the same expandable and contractible, and being provided with a tapered portion 18, to engage a correspondingly tapered seat 19 in the nut 15. By turning the clamping screw in the proper direction, the rod 14 may be released and moved axially to the desired position, to focus the bulb, after which, said screw may be turned to 80 clamp the rod in such position. The latter may be provided with a knurled end 20 to facilitate grasping the rod to adjust the same. It should be understood that the described focusing means *per se* forms no part 85 of my present invention, but is shown and described because of its association with and adaptation to the electrical connections which I will now describe.

The bulb 13, herein shown, is of the 95 well-known "Ediswan" type, the same being provided with a base 21, having laterally projecting pins 22, to engage bayonet slots 23 in a socket member 24, the latter forming a part of the connection. Lamps and connections of this type are of two styles, one for single wire and the other for double wire systems. The form shown in Figs. 2, 3 and 4, is of the two-wire style, while that shown in the modification in Fig. 5 is for a 100 single-wire system, the essential difference between the two being that one has two terminals to which two conducting wires are connected, while the other has a single terminal to which a single conducting wire is 105 connected.

Referring to Figs. 2, 3 and 4, I have

shown a pair of conducting wires 25, which may be and are herein provided with suitable terminals 26, which extend into channels 27 in an insulating member 28, within which they are connected to suitable contacts. In the present example, these contacts are of common form, and comprise spring-pressed plungers 29, mounted to slide in plunger-guides 30, which inclose usual 10 springs 31, acting in a familiar manner to press their respective plungers in an outward direction into engagement with the terminals of the lamp base, or other device which occupies the socket 24. Preferably, the plunger guides 30 are directly attached to the terminals 26, by providing said guides with reduced portions 32, passing through said terminals, and headed over to form rivets. By this means, it is impossible for the terminals to become detached from the plunger guides. This arrangement, moreover, is a factor in attaching the plunger guides to the insulating member 28, as will presently appear.

25 In the present example, the insulating member 23 is provided with a boss 33, extending into the socket member 24, and is provided with holes 34 to receive the plunger guides 30. Preferably, the channels 27 30 are closed by a second insulating member 35, thus effectually insulating the conductors, and preventing any danger of short circuits.

As a means for securing the socket member, the insulating members, and the conducting members, together, I have herein provided a simple form of clamping means comprising a clamping plate 36, threaded to receive one or more clamping screws 37, 40 which extend through the insulating members 28 and 35, and also through a second clamping member 38, the latter being herein in the form of an integral flange formed on the socket member 24. As a means for insuring correct assembling of the parts, I have herein provided the insulating member 28 with a plurality of bosses 39 located in apertures 40 in the flange 38, and have provided said insulating member with a plurality of 45 bosses 41, extending through apertures 42 and 43 in the parts 35 and 36, respectively, as best shown in Fig. 4.

It should now be evident that it is an easy matter to assemble the parts rapidly, and yet without error, and finally to secure them together, by simply inserting the clamping screws 37 and tightening them, thereby clamping all the parts firmly together. When once united, there is no danger of 55 accidental separation of the parts, nor is there any danger of short circuiting. The parts may be readily dismounted, however, at any time, by simply removing the clamping screws 37, whereupon the conducting elements may be entirely removed from

the insulating member 28, and the latter removed from the socket member 24.

Referring now to the second form of my invention illustrated in Figs. 6, 7, 8 and 9, I have there shown an electrical connection 70 comprising a socket 44, to receive an insulating member 45, in which is mounted a plunger guide 46, having a spring-pressed plunger 47 working therein. The insulating member 45, in this example, is provided with 75 a laterally-extending channel 48, to receive a conducting wire 49, the latter having its terminal portion 50 secured to the plunger guide 46 in any suitable manner, as by providing the latter with a hole 51, to receive 80 the wire. The latter may be soldered in place in the hole, if desired.

As a means for securing the insulating member 45 in the socket 44, and for securing the plunger guide 46 and wire 49 in 85 place in said insulating member, in the present instance, I have provided a plurality of clamping screws 52, extending through a clamping plate 53, into flanges 54, formed on the socket member, as best shown in Fig. 90 6. As a means to limit the inward movement of the insulating member 45 in the socket member 44, I have herein provided the latter with suitable abutments 55, against which the inner end of the insulating member is brought. By this means, the parts are securely clamped together. Preferably, a second insulating member 56 is interposed between the clamping plate 53 and the flanges 54, thus closing the channel 48, except at its entrance, where the conducting wire 49 leads into the insulating member. If desired, the socket member 44 may be indented, as at 57, to retain the insulating member 45 in place, but I have found in 100 practice that this is not necessary, as the parts are very securely held together by the described clamping means. The omission of the indentation has the further advantage of permitting the parts to be readily dismounted, and reassembled at will.

Referring now to Fig. 9, which shows a slight modification of the form illustrated in Figs. 6, 7 and 8, the construction is precisely the same as that just described, except that I have provided two sets of conductors including wires 49 and plunger guides 46, the same as those just described in connection with Figs. 6, 7 and 8, thereby to adapt the connection to a two-wire system.

While I have herein shown and described two forms or embodiments of my invention, and have disclosed and described in detail the construction and arrangement incidental to two specific applications thereof, it is to be understood that my invention is limited neither to the embodiments herein shown, nor to the mere details or relative arrangement of parts, but that extensive 125 130

deviations from the illustrated forms or embodiments of the invention may be made, without departing from the principles thereof.

5 Having thus described my invention, what I claim and desire by Letters Patent to secure is:

1. In a device of the class described, the combination of a socket member, an insulating member extending into said socket member and provided with a lengthwise bore and a transverse channel, a terminal mounted in said bore, a conductor extending into said channel and connected to said terminal, an insulating member overlying said channel, and means to secure said insulating members together thereby to hold said terminal in said bore and said conductor in said channel.
- 10 2. In a device of the class described, the combination of a socket member, an insulating member extending into said socket member and provided with a lengthwise bore and a transverse channel, a terminal mount-

ed in said bore, a conductor extending into 25 said channel and connected to said terminal, an insulating member overlying said channel, and means including a clamping member and clamping screw to secure said insulating members together thereby to hold said 30 terminal in said bore and said conductor in said channel.

3. In a device of the class described, the combination of a socket member provided with a lateral flange, an insulating member 35 extending into said socket member and provided with a lengthwise bore and a transverse channel, a terminal mounted in said bore, a conductor extending into said channel and connected to said terminal, an insulating member overlying said channel, and means extending into said flange to secure 40 said insulating members together thereby to hold said terminal in said bore and said conductor in said channel.

In testimony whereof, I have signed my name to this specification.

ELLSWORTH A. HAWTHORNE.
